UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

GAS-GENERATING APPARATUS.

Application filed May 16, 1921. Serial No. 469,977.

This invention relates to gas generation, and more particularly to apparatus for generating producer gas.

One of the objects of the invention is to provide apparatus for generating gas for use in gas engines, which furnish the suction for operating the producer.

Another object of the invention is to provide such a gas generating set in which the heat in the exhaust gas from the engine is utilized in the apparatus for supplying moisture to the producer.

Another object of the invention is to provide an improved method of supplying moisture to a gas generating system, and apparatus for carrying out that method.

Another object of the invention is to provide suitable apparatus for purifying the generated gas.

Other objects and advantages of the invention will be apparent from the description thereof set out below when taken in connection with the accompanying drawing.

In the drawing, in which like characters of reference designate like parts throughout the several views thereof,

Fig. 1 represents, somewhat diagrammatically, a gas generating system embodying the invention, certain of the parts thereof being shown in section and certain other parts in elevation, to more clearly bring out the features of the invention;

Fig. 2 is a horizontal sectional view through the generator along the line 2—2 of Fig. 1;

Fig. 3 is a sectional view through the lower part of the producer or generator, along the line 3—3 of Fig. 2;

Fig. 4 is a sectional view through the vaporizer, along the line 4—4 of Fig. 1;

Fig. 5 is a sectional view through a modified form of vaporizer;

Fig. 6 is a sectional view through still another modified form of vaporizer;

Fig. 7 is a sectional view through the filter mechanism used in connection with the invention; and

Fig. 8 is a view of another form of generating system, fundamentally similar to the system shown in Fig. 1 but having a different form of purifier and a different form of moisture supply apparatus.

The gas generating system embodying this invention is illustrated in connection with a gas producer, which is suction operated,

the suction being caused by a gas engine, direct connected to the gas generator and serving, to cause a flow of air and moisture through the fuel bed within the generating chamber of the producer to bring about the generation of gas, which gas is fed into the combustion chamber of the engine. In the form of apparatus shown, somewhat diagrammatically, in Fig. 1, the producer or generator, proper, comprises a cylindrical metallic shell 10, the upper part or zone of which comprises a fuel reservoir and the lower part, or zone, the generating chamber. The lower end of the shell 10 is closed by means of a plate 11, which is supported in place upon bolts 12, the upper ends of which are supported by the ring 13, which is, in turn, rigidly attached to the shell 10, as by riveting. The lining for the generating zone is supported upon the closure plate 11. This lining comprises a lining proper 14 which, as shown in the drawing, consists of a plurality of fire brick. These brick may be of varying form but a preferred form is shown in the drawing, particularly Figs. 1 and 2. As shown these brick are so formed

that when in place they provide a cylindrical fuel receiving chamber, or generating zone proper, designated generally by the numeral 15, the upper layer of brick being of somewhat different form, so that the upper end of the generating zone flares outwardly, or is funnel shaped, to facilitate the flow of fuel from the reservoir 16 into the generating zone proper. The brick constituting the generating zone proper, as shown best in Fig. 3, have their backs hollowed out to provide a trough shaped hollow space therein with supporting legs. The difference in construction between the brick forming the generating zone proper and those in the funnel shaped part of the generating zone is thought obvious from the drawing. The form of brick shown is not essential, but constitutes a satisfactory type of lining material. It is desirable, in the operation of the producer forming a part of this invention, that the fire brick lining shall have less heat capacity than is normally present in the lining of a producer of corresponding size. Consequently the fire brick 14 are made in the hollow form shown, the construction decreasing the heat capacity without decreasing, to an objectionable degree, the strength of the brick. Filling the hollow

110

spaces within the brick, and between the brick and the metallic shell 10, is suitable heat insulating material 20. This heat insulating material may be of any desired character, but it has been found that a mixture of the material known, commercially, as "silocel", which consists primarily of kieselguhr and cement, in the proportion of four parts to one, will give very satisfactory results. But any material which is a good heat insulator will probably function satisfactorily. Except for the greater strength, and greater resistance to wear, the fire brick lining might be dispensed with entirely, and the entire lining of the generating zone built up of heat insulating material.

At the bottom, adjacent the closure plate 11, the lining is cut away to form an ash pit designated generally 21, which at one end is in communication with the lower end of the generating zone 15, and at the other end is in communication with an opening 22 provided in the metallic shell 10, to permit access to the ash pit. As shown most clearly in Fig. 2 a special form of fire brick 23 is used to define the ash pit opening, but another form of brick may be used if desired. A supporting brick 24 is placed over the ash pit adjacent the door to support the heat insulating material directly above the ash pit.

Supported upon the brick defining the ash pit is a metallic member 25, which, as shown most clearly in Figs. 1 and 3, is adapted to receive and support the grate 26. This grate consists of a circular metallic disc, of a suitable material, such as steel or cast iron, having openings or passages therein, as shown in Fig. 2, to permit the passage of ashes therethrough into the ash pit. A handle 27 for sliding the grate into and out of position is provided. When the grate is in position it closes the lower end of the generating zone 15 and supports the fuel bed within the generating chamber. The construction is such, however, that the grate is maintained out of thermal contact with the metallic shell 10 of the producer, the member 25 which supports it being carried entirely by the lining and not in thermal contact with the shell. This mounting minimizes the transfer of heat from the incandescent fuel within the generating chamber through the grate to the metallic shell 10 whence it would be radiated into the atmosphere, and thus materially decreases the loss of heat from the fuel bed of the generating zone. It has been found that this decrease in heat loss has a very important bearing upon the blowing up or starting period of the producer, and also upon the operating of the producer after the blowing up or starting period has been completed.

The upper end of the shell 10 is closed by means of a closure plate 30 which is posi-

tioned a short distance from the end of the shell to provide a trough 31. A fuel supply opening 32 is provided within this closure plate through which fresh fuel is introduced into the fuel reservoir 16, whence it passes into the generating zone to replenish the fuel therein as it is consumed. Surrounding the fuel supply opening 32 is an upstanding flange 33, the upper end of which preferably extends even with or above the upper end of the shell 10. The trough 31, during operation, contains a supply of water, and the upstanding flange 33 should extend sufficiently high to permit of maintaining a suitable supply of water in this trough. A cover member 34 is provided for the opening 32, which consists of an inverted cup shape member the edges of which extend downwardly into the water in the trough 31, which also serves to seal the opening 32 and prevent the inflow of air into the producer, therethrough, during operation.

Leading off from the top of the reservoir 16 is an offtake pipe 35, a baffle member 36 depending from the closure plate 30, adjacent the opening into the offtake pipe, to prevent the fuel within the reservoir working into this pipe and clogging it. Leading off from the offtake pipe is a branch pipe 40 to which is attached a blower 41, preferably of the centrifugal type, operated by means of an electric motor 42, connected to any suitable source of current. A valve 43, of any conventional construction, is inserted within, and controls, the pipe 40. The outlet of the blower 41 is connected to a vent pipe 44, a small bleed pipe 45 opening from the vent pipe beyond the blower, so that so long as gas is being forced through the vent pipe by the blower 41 some gas will also escape through the bleed pipe 45. The offtake pipe 35 is also connected to a purifier 50, a valve 51 of any desired conventional construction being inserted in the pipe between the valve 43 and the purifier, to control connection between the purifier and the offtake pipe. This purifier consists of a cylindrical metallic chamber containing a layer of sawdust, shavings, or the like. The offtake pipe, as shown, opens into the purifier adjacent the bottom thereof, and the outlet pipe 52 through which gas passes from the purifier, opens therefrom adjacent the top, so that any gas which passes into the purifier must pass through the sawdust or shavings therein on its way out through the pipe 52. A baffle 53, which consists of a V shaped trough like member, supported upon the rod 54, is mounted within the purifier between the opening of the offtake pipe thereinto, and the opening therefrom into the outlet pipe the construction being such that the gas introduced into the purifier must pass around the baffle plate in order to escape. The gas is thus forced to take a

circuitous path and its time of contact with the purifying material is increased so that a greater cleaning action is secured. Openings 55, provided with suitable closures 56 are provided in one end of the purifier through which material may be introduced into and withdrawn from the purifier for replenishing the cleaning material. Any other suitable type of purifier may be used.

10 One very satisfactory form is shown in the patent of Harry F. Smith No. 1,099,773, issued June 9, 1914. Still another desirable form is that shown in the application of Harry F. Smith, Serial No. 398,749, filed

15 July 24, 1920.

The outlet pipe 52 opens into a cooler 60, within which the temperature of the gas is lowered to bring it to substantially atmospheric temperature. Any desired type of 20 cooler may be used, the form shown in the drawing consisting of five sections of standard steam radiator, the gas being introduced at the top of the radiator sections and withdrawn at the bottom so that a maximum 25 cooling effect is secured. The gas is withdrawn through a delivery main 61, which is attached at one end to the cooler, and at the other end to the inlet to the gas engine adapted to operate upon the generated 30 gas.

The engine is not shown in detail since the invention is applicable to any type of gas engine adapted to operate upon producer gas. The engine, therefore, is merely 35 shown diagrammatically, in elevation, the showing corresponding with the well-known Delco-light engine, which is illustrated and described in the patent of Charles F. Kettering and William A. Chryst, Number 1,341,-

40 327, dated Mar. 25, 1920.

The exhaust gases from the engine pass off through the exhaust pipe 63 which has inserted therein a vaporizer for supplying moisture to the producer. This vaporizer 45 consists of a body member 64 the opposite ends of which are connected to the cooperating ends of the exhaust pipe 63. A hollow cover member 65 is provided for this body member, the space therein serving as a vaporizer, or flash boiler, a clean-out opening being provided in the upper wall thereof which is normally closed by the plug 66. The lower wall of this hollow cover member is provided with depending ribs or flanges 50 67, which extend downwardly into the body member 64 where they are subjected, when in position, to the hot exhaust gases as they pass through the body member. The purpose of these ribs or flanges is to increase the amount of heat which passes from the 55 exhaust gas into the flash boiler. Leading into the flash boiler, and terminating adjacent the bottom thereof is a water supply pipe 70, the other end of which opens 60 through the shell 10 into the bottom of the

trough 31, a filter member 71 being provided to prevent the passage of impurities into the vaporizer. A valve 72 is inserted within the pipe 70 to control the flow therethrough. Leading off from the flash boiler adjacent 70 the top thereof is a pipe 75, which extends upwardly from the boiler such a distance that its highest point is above the highest level of water within the trough 31, the pipe being in the form of an inverted U, the 75 lower end of the pipe passing through the shell of the producer and opening into the passage 76 which terminates within the ash pit beneath the grate. A needle valve 77 is inserted within the pipe 75 so that very accurate control of the effective opening through the pipe may be secured.

In the operation of the device, fuel having been supplied to the generating zone and ignited, the valve 51 is closed and the valve 43 opened, to connect the generator to the vent pipe. The blower 41 is then started, causing a blowing up of the fuel bed, the products of combustion during this blowing up or starting period being vented to atmosphere through the pipe 44. As these gases pass through the pipe 44 a small quantity of gas also escapes through the pipe 45, and the gas which thus escapes is tested from time to time to see whether or not it is of sufficiently good quality to burn. As soon as the gas becomes of such good quality that it will burn, the blower is stopped, the valve 43 closed, shutting off connection between the producer and the vent, and the valve 51 opened, connecting the producer to the purifier, and so to the inlet pipe 62 of the engine. The engine is now started, the suction caused by the turning over of the engine, drawing gas into the cylinder, which being combustible, will ignite to cause operation of the engine. The engine, therefore, will continue to operate and during operation will draw gas into its cylinder, the suction at the same time causing a flow of air and moisture, through the fuel bed to generate gas. As the hot exhaust gases pass through the vaporizer, the lower wall of the cover member 65 will become heated. Inasmuch as the space within the ash pit is under suction, water will flow from the trough 31 into the flash boiler, when the valves 72 and 77 are open. As water flows from the pipe 70 into the vaporizer it will be changed into steam which will tend to pass off through the pipe 75 to the ash pit of the producer, and also to back up within the pipe 70. By making the highest point in the pipe 75 above the highest level of water within the trough 31 the flow of water into the vaporizer can be readily controlled, for the valve 77 is so positioned as to permit the desired quantity of steam to pass therethrough into the ash pit. There being a restricted opening at the valve 77 the pres. 130

sure of the steam within the vaporizer will build up, and the device will function automatically to control the quantity of moisture fed thereto, and thus control the quantity of steam. As the pressure of the steam builds up it will tend to back the water up the pipe 70. The amount of water which flows through the pipe 70 is thus automatically controlled and, therefore, the amount 10 of moisture which is fed to the generator.

In Fig. 5 is shown a slightly modified form of vaporizer. In this vaporizer the body member 64 and lower wall of the cover 65, with its ribs or flanges, are made integral, 15 the resulting member being designated by the numeral 78. The ribs thus become the separators or partitions 79 which divide the member 78 into a plurality of passages through which the exhaust gases pass on 20 their way through the vaporizer. The member 78 is provided with a depression in the top thereof which serves to receive the water to be vaporized, a flat top or cover 80 being provided which corresponds to the upper 25 wall of the cover member 65. Opening through the cover 80 is the pipe 70' through which moisture is supplied and also the pipe 75' through which the vapor generated within the vaporizing space proper, 81, passes 30 to the generating chamber of the producer. A drain passage 82 controlled by the plug 83 is provided for cleaning out the vaporizer 35 space 81. The operation of this form of vaporizer is substantially identical with that described above.

In Fig. 6 is shown a modified form of vaporizer in which the cover member 84 has two passages 85 and 86 therein adapted 40 respectively for attachment to the opposite ends of the sections of exhaust pipe, each of these passages opening through the lower face of the cover member. Cooperating with the lower face of the cover member is a hollow cup shaped member 87, the interior 45 of which is connected to the ends of the passages 85 and 86 which open through the lower face of the cover member 84. This member 87 is preferably composed of some metal which is a good conductor of heat, 50 such as aluminum. The member 87 is rigidly attached to the cover member 84 by means of a bolt 88 threaded into the member 87, the cover member 84 and member 87 being pulled tightly together by means of 55 the nut 89 upon the bolt 88 which nut cooperates with the upper surface of the member 84. Surrounding the cup shaped member 87 and spaced therefrom is a similar cup shaped member 90, the upper edge of which, 60 when in assembled position, contacts with the lower face of the flange 91, carried by the member 87, the upper face of which flange cooperates, when the device is assembled, with a corresponding surface of 65 the lower face of the cover member 84, suit-

able packing being interposed between the contacting faces to make tight joints. The members 87 and 90 are held in properly assembled position by means of a hollow bolt 92, the inner end of which is threadedly engaged within the member 87, a nut 93 being threaded upon this hollow bolt, and coacting with the lower face of the member 90 to hold the two in tightly assembled position. The member 90, where the bolt 92 passes 75 therethrough, is provided with a stuffing box 94 adapted to contain any suitable packing material 95, the packing gland 96 cooperating therewith, and with the nut 93 so that upon tightening the nut to hold the members 80 in assembled position, the packing will at the same time be properly compressed to prevent the escape of moisture therethrough. The hollow bolt 92 is attached at its outside end to the pipe 97 which leads to a suitable 85 source of moisture supply, as for instance the trough 31. Radial passages 98, are provided in the bolt 92 for connecting the passage in such bolt to the space between the members 97 and 90, water thus being fed 90 from the pipe 97 into this space. Leading off from the space between the two members 87 and 90, at the top thereof, is a vapour supply pipe 99, through which the vapor generated from the water within the space between the two members 87 and 90 is led to 95 the generating zone of the producer.

In Fig. 7 is shown the type of filter mechanism used. This consists of two members 150 and 151 which are threaded together, 100 a layer of filter material 152, which may be of any desired character, being held between them. This type of filtering mechanism may be dispensed with if desired and any other satisfactory type of filtering mechanism substituted therefor.

In Fig. 8 is shown a slightly modified form of the invention in which a different form of moisture supply apparatus and a different form of purifier is provided. The 110 producer used in the modification shown in this figure is identical with that shown and described above in connection with Fig. 1. The producer, for purposes of description, 115 being designated by the numeral 100. The gas generated within the producer is led off therefrom through the offtake pipe 35', the same form of blower 41' being connected to the offtake pipe and delivering into the 120 vent pipe 44', as described above. In the modification shown herein the cooler 60 is dispensed with, the gas being led directly into a purifier and thence to the intake of the gas engine. While the cooler 60 is desirable under some conditions, it may often 125 be dispensed with without in any way affecting adversely the character of the gas as delivered to the gas engine, sufficient cooling action taking place as the gas passes through the delivery pipe, and the purifier, 130

to the gas engine. The gas from the offtake 35 passes into the purifier, which, in the modification shown consists of a vertical cylindrical metallic shell 105 having a cover 106, provided with a groove 107 within which the upper edge of the cylindrical shell 105 is disposed when the cover is in place, suitable packing material, of any desired character, being provided within the groove 108 to make a tight joint. A plurality of clamping bolts 108, rigidly attached to the shell 105, and adapted to project upwardly through corresponding passages within the cover 106 are provided for clamping the cover in place. Each of these bolts has its upper end threaded and a nut 109 cooperating therewith by means of which the cover plate is clamped tightly in place. Rigidly secured to and depending from the lower face of the cover 106 is a cylindrical sleeve 110, preferably of some suitable metal, such as steel, which is of smaller diameter than the internal diameter of the cylindrical shell 105, and extends downwardly into the shell 105, terminating a short distance from the lower end thereof, and is of such dimensions as to provide a considerable space between the two shells 105 and 110. The offtake pipe 35' opens through the top 105 in such wise that the gas passing into the purifier is introduced into the space within the depending flange or shell 110. Supported from the top 106 is a cup shaped plate 115, to which is secured the upper end 30 of a sleeve of filtering material 116, the lower end of this sleeve 116 being secured within the constricted lower end of the shell 110. This sleeve preferably consists of a fibrous or textile material such as burlap or some other good filter material. The upper end of this sleeve is secured to the member 115 by means of spring clips 117, the lower end being correspondingly secured with the constricted lower end of the shell 45 110 by means of the clips 118. This construction is such that the gas introduced into the shell 110 through the offtake pipe 35' must pass through the sleeve 116 of filtering material on its way to the delivery pipe 52', 50 which opens from the space between the shell 110 and the shell 105. As the gas passes through the sleeve 116 the impurities are removed therefrom, the gas as delivered to the intake of the engine 63' being thus substantially free from impurities and suitable for satisfactory operation of the engine. 55

Any type of purifier may be substituted in lieu of those shown in Fig. 1 and Fig. 8 these two forms being merely modifications which have functioned satisfactorily in use. As stated above each of these two types of purifiers is primarily designed for use with a gas generated from charcoal, coke, anthracite coal, and the like, which give a gas con-

taining small quantities of tar and similar impurities. If bituminous coal, or analogous fuel, were used in the producer a purifier adapted to handle, satisfactorily, the larger quantities of tar which are present in gas generated from such a fuel should be substituted in place of the purifier described. The moisture control apparatus shown in Fig. 8 is adapted to give accurate control. The vaporizer proper is inserted within the exhaust pipe 63', and consists of a body member 119 similar in construction to the member 64 shown in Fig. 1. This body member is provided with a vaporizer or boiler 120, which also serves as a cover member therefor, being held in place by means of suitable bolts 121. The boiler 120 is in turn provided with a cover 122 held in position on the boiler by means of suitable bolts 123. Opening into the boiler, through the top 122 thereof is a water supply pipe 125, a plurality of shelves or trays 126 being suspended within the boiler, beneath the opening in the end of this pipe, so that any water fed therethrough into the boiler will spread out over the trays 126, passing from tray to tray through the perforations 127 therein, finally dripping onto the lower wall of the boiler 120 where it will be vaporized. The trays or shelves 126 serve to collect any lime or other substances that may be in solution in the water, such impurities being thrown down on the trays as the water trickles over them, and the incrustation of the lower wall of the boiler 120 being thus largely prevented. From time to time the top 122 can be removed, the trays 126 taken out of the boiler and cleaned. Leading off from the boiler 120 adjacent the top thereof is the vapor supply pipe 75' through which the steam generated in the boiler passes to the ash pit of the producer.

The pipe 125 opens, at its other end, into a trough or vessel 130 to which water is supplied from the trough 31' of the producer. The filter member 71' is attached to that end of a pipe 131 which is within the trough 31', the opposite end of the pipe 131 opening into the U shaped pipe 132. One end 133 of the U shaped pipe 132 opens into the exhaust pipe 63', the other end 134 terminating above the trough 130. As the engine operates the impulses within the exhaust pipe 63' will pump water from the trough 31' and deliver it through the end 134 of the U shaped pipe 132 into the trough or vessel 130. The trough 130 is divided by means of the partition 135 into two main compartments 136 and 137, the end 134 of the pipe 132 being so positioned as to deliver water into the compartment 136, an overflow 138 being provided to prevent the level of water within the compartment 136 rising too high. The compartment 137 is also divided by means of the partition 140 into

two smaller compartments 141 and 142, the pipe 125 opening into the compartment 142, through the bottom thereof. A passage 145 connects the compartment 136 to the compartment 141 and permits the flow of water from the compartment 136 into the compartment 141. The partition 140 controls the level of the water within the compartment 141, this partition being of such height that its upper level is below the overflow orifice 138. The level of the water within the compartment 141 is thus maintained constant, a definite differential being thus established between the level of the water in the compartment 141 and the level of the water in the compartment 136. A definite head therefore exists which causes the water to overflow the partition 140 at a rate which is constant and dependant upon this head. The water which overflows the partition 140 passes into the compartment 142 and thence through the pipe 125 into the boiler 120.

As the system shown in Fig. 8 operates the exhaust impulses within the pipe 63 acting upon the water within the U tube 132 pump that water into the compartment 136. The apparatus is so constructed that during operation enough water will be pumped to provide sufficient moisture for the producer.

While the method herein described, and the forms of apparatus for carrying this method into effect, constitute preferred embodiments of the invention, it is to be understood that the invention is not limited to this precise method and forms of apparatus, and that changes may be made in either without departing from the scope of the invention which is defined in the appended claims.

What is claimed is:

1. A gas generating system comprising in combination, a producer; a gas engine connected thereto and adapted during operation to furnish the suction for causing operation of the producer; and a flash boiler vaporizer associated with the exhaust of the engine, said vaporizer being connected to the air supply of the producer to supply moisture thereto during operation and means for feeding water to said boiler at a rate proportionate to the rate of gas generation.

2. A gas generating system comprising in combination, a producer, having a water reservoir carried thereby and so positioned that the water in said reservoir will receive heat from the gas generated within the producer; a gas engine connected to the producer and adapted to operate upon the gas generated therein, and to furnish the suction for operating said producer; a flash boiler associated with the exhaust of said engine, a water supply pipe connecting the interior of said flash boiler to the water reservoir, and a vapor supply pipe connecting the interior of the flash boiler to the air supply

of the producer, and means for controlling the feeding of water from the reservoir to the boiler in accordance with the rate of gas generation.

3. A gas generating system comprising in combination, a producer, having a water reservoir carried thereby and so positioned that the water in said reservoir will receive heat from within the producer during operation thereof; a gas engine connected to the producer and adapted to operate upon the gas generated therein, and to furnish the suction for operating said producer; a flash boiler associated with the exhaust of said engine, a water supply pipe through which water from said reservoir passes into the interior of said flash boiler, and a vapor supply pipe connecting the interior of the flash boiler to the air supply of the producer, the construction being such that the amount of water fed to the flash boiler is automatically controlled in accordance with the amount of air drawn in through said air supply by the suction of the engine.

4. A gas generating system comprising in combination a producer, having a water reservoir carried thereby and so positioned that the water in said reservoir will be heated during operation of the producer; a gas engine connected to the producer and adapted during operation to cause suction for operating said producer; a flash boiler associated with the exhaust of said engine, a water supply pipe through which water from said reservoir is fed into the flash boiler, a vapor supply pipe connecting the interior of the flash boiler with the interior of the producer, and means for automatically controlling the supply of water to the flash boiler to regulate the quantity of vapor introduced along with the air supply into the interior of the producer, in accordance with conditions within the producer.

5. A gas generating system comprising in combination, a producer, a water reservoir carried thereby and so positioned that the water in said reservoir will be heated during operation of the producer; a gas engine connected to the producer and adapted during operation to furnish the suction for operating the producer; a flash boiler associated with the exhaust of the engine, a water supply pipe through which water from said reservoir is fed into the flash boiler, automatic means for controlling the rate of transfer of water from the reservoir to the flash boiler to insure a uniform, predetermined rate of supply of water to the flash boiler, and a pipe connecting the flash boiler to the interior of the producer for leading the generated vapor into the air supply for the producer.

6. A gas generating system comprising in combination, a producer; a gas engine receiving gas for its operation from the pro-

- ducer; a vaporizer associated with the exhaust of said engine; a constant level tank connected to said vaporizer; and means for supplying water to said tank to maintain the level of the water therein during operation of the producer constant, said means including an impulse pump operated by the impulses within the exhaust pipe of the engine.
- 10 7. A gas generating system comprising in combination, a producer; a gas engine receiving gas for its operation from the producer; a vaporizer associated with, and positioned to receive heat from, the exhaust of said engine, a vapor supply pipe connecting the vaporizer to the air supply of said producer; a water receiving tank, a pipe connecting said tank to the vaporizer for feeding water therefrom into the vaporizer; means for supplying water to said tank comprising a U tube having one end connected to the interior of the engine exhaust pipe, the other end positioned to discharge into the said tank and means connecting the said U tube, intermediate its length, to a source of water supply, the construction being such that water will be urged from the U tube into the tank under the action of the pressure impulses within the exhaust pipe, and means within the tank for maintaining uniform the rate of supply of water passing therefrom into the vaporizer.
8. In a gas generating system, the combination with a producer and a gas engine receiving gas for its operation from the producer; of a vaporizer associated with and positioned to receive heat from the exhaust of said engine, a vapor supply pipe connecting the vaporizer to the air supply of the producer; a water receiving tank, a main partition, having a constant orifice therein, dividing the tank into two main compartments, an overflow orifice from one of said compartments, a second partition dividing the other compartment into two smaller compartments, said second partition terminating below the level of the said overflow orifice, means for supplying water to said first compartment at a rate in excess of the rate of flow of water through the orifice in the main partition in the second compartment, and a pipe connecting the

vaporizer with that one of the two said smaller compartments into which the said constant orifice does not open.

9. In a gas generating system, the combination with a producer and a gas engine receiving gas for its operation from the producer; of a vaporizer associated with and positioned to receive heat from the exhaust of said engine, a vapor supply pipe connecting the vaporizer to the air supply of the producer; a water receiving tank, a main partition, having a constant orifice therein, dividing the tank into two main compartments, an overflow orifice for one of said compartments, a second partition dividing the other compartment into two smaller compartments, said second terminating below the level of the said overflow orifice, an impulse pump operated by pressure impulses within the exhaust of the gas engine for supplying water to said first compartment at a rate faster than the rate of flow of water through the orifice in the main compartment into the second compartment, and a pipe connecting the vaporizer with that one of the two said smaller compartments into which the said constant orifice does not open.

10. A gas generating system comprising in combination a gas producer, a gas engine receiving gas for its operation from said producer; and a vaporizer comprising a flash boiler associated with and positioned to receive heat from the exhaust of said engine, a water inlet for said vaporizer, means for supplying water to said vaporizer therethrough at a controlled rate, an outlet for the vapor generated from said water connected to the air supply of the producer, and a plurality of perforated trays positioned beneath the water inlet.

11. A gas generating system comprising, in combination, a producer; a gas engine receiving gas for its operation from the producer; a vaporizer associated with the exhaust of said engine; and means for supplying water to said vaporizer including an impulse pump operated by the impulses within the exhaust pipe of the engine.

In testimony whereof I hereto affix my signature.

HARRY F. SMITH.
